Watson E. Coleman
ATTORNEY.

UNITED STATES PATENT OFFICE.

JESSE R. SMITH, OF GREENFIELD, ILLINOIS, ASSIGNOR OF TWENTY-FIVE PER CENT. TO CARSON A. LINDER AND TWENTY-FIVE PER CENT. TO FLOYD L. OWENS, BOTH OF GREENFIELD, ILLINOIS, AND TWENTY-FIVE PER CENT. TO DEAN CORSA, OF WHITE HALL, ILLINOIS.

GARMENT-SUPPORTER.

1,387,912.

Specification of Letters Patent. Patented Aug. 16, 1921.

Application filed September 15, 1920. Serial No. 410,410.

To all whom it may concern:

Be it known that I, JESSE R. SMITH, a citizen of the United States, residing at Greenfield, in the county of Greene and State 5 of Illinois, have invented certain new and useful Improvements in Garment-Supporters, of which the following is a specification, reference being had to the accompanying drawings.

10 This invention relates to certain improvements in garment supporters, and has relation more particularly to a novel and efficient resilient attaching loop which is capable of general application.

15 An important object of the invention is to provide a device of this character which may be readily attached or detached from the support proper in the application or removal of the loop; but which loop may not 20 be detached by strain applied in a straight line thereon.

A further object of the invention is to 25 provide an attaching loop which is resilient and which may be deformed to permit its attachment to, or removal from, the support proper, and which resiliency opposes separation of the garment secured to the attaching loop and the support proper; but which may not be removed from the support 30 proper by any strain placed thereon by the garment attached thereto.

A further object of the invention is to 35 provide a resilient attaching loop provided at its upper end with arcuately curved oppositely directed arms which are adapted to extend through and co-act with the edges of an opening formed in a loop or pocket of the support proper, whereby downwardly exerted force upon the loop brings into play 40 resilient resistance of the arms at the sides of the opening thereby resiliently resisting such downward force.

A still further object is to provide an attaching loop of this character, the upper 45 ends of the arms of which are provided with angular portions preventing removal of the attaching loop by force exerted at the attaching portion thereof.

Other objects and advantages of the invention will become apparent throughout the course of the following description:

In the accompanying drawings, wherein for the purpose of illustration, like refer-

ence characters designate like parts throughout:

Figure 1 is a side elevation partly in section of a garment supporter constructed in accordance with my invention, showing in dotted lines the position of the attaching loop when strain is applied thereto, and 60 Fig. 2 is a similar view of a slightly modified form of my invention.

As disclosed in the accompanying drawings, S designates a strap included in my improved garment support which is preferably non-flexible and which has its lower portion returned upon itself as at 1 to form a loop or pocket 2, and the bend or under portion 3 of the loop is provided with a reinforcing strip 4 of leather, canvas or other 70 suitable material, and said bent or outer portion is likewise provided with an opening 5, reinforced preferably by a metallic ferrule or eyelet 6.

An attaching loop 7 is provided having 75 the lower end thereof shaped to conform to the article to which it is attached, being shown in the preferred form of my invention as adapted for attachment to a button, and in the modified form, as provided with 80 a restricted V-shaped portion 9 adapted to receive therein a fold of cloth and hold the same by friction. The side arms 10 of the attaching loop preferably diverge somewhat upwardly and are provided at their upper 85 ends with spring loops 11, terminating in substantially horizontal portions which have their ends extending upwardly and diverging, as indicated at 13. These ends or arms 13 are preferably arcuately curved and are 90 provided upon their extremities with returned hook portions upon the under-surface thereof for a purpose presently to appear, the curvature of the arms having the concavity thereof downwardly directed. 95

These arms extend through the reinforced opening 5 and may be positioned therein by placing the end of one arm in the opening and then deforming the other arm to permit its insertion. After such insertion, a 100 direct pull upon the loop at the attaching portion thereof may not remove the arms from their engagement in the reinforced opening by reason of the fact that the extremities 14 thereof engage the sides of the 105 openings and prevent such removal. It will

be obvious that the attaching loop and arms being formed of resilient material, such as spring wire, any downward force exerted upon the attaching loop will be resiliently opposed by the arms 13, and by the fact that these arms being divergent necessitates the deformation of the attaching loop 7 to permit their passage through the reinforced opening 5 by such direct pull. The loops 10 11 being formed at the upper ends of the side arms 10 of the attaching loop permit of a larger degree of deformation at this point without materially altering the formation of the loop in general. In fact the 15 lower portion of the loop, the side arms 10 and attaching portion 8 may, if preferred, be formed in such a manner that they are set against the deformation. It will be obvious that if it is desired for any reason, to 20 remove the attaching loop from the loop or pocket 2, this may readily be done by a slight deformation of the arms to permit the ends thereof to pass through the openings.

25 It will further be obvious that my device by reason of its simplicity and general efficiency and use, and ease of which it may be assembled and manufactured, is particularly adapted for the use for which it is intended, and it will likewise be obvious that 30 the construction hereinbefore set forth is capable of some change without departing from the spirit of my invention. I, accordingly, do not limit myself to the specific 35 structure set forth, except as so limited by the subjoined claims.

What I claim is:

1. The combination with a supporting strap embodying a loop, said loop having an 40 opening formed therein, of an attaching member embodying arms extending through the opening of the loop and normally dis-

posed within the loop, said arms resiliently resisting their withdrawal through said opening by a pull on said member and returning to their normal position within said loop when said pull is discontinued. 45

2. The combination with a supporting strap embodying a loop, said loop having an opening formed therein, of an attaching 50 member embodying arms extending through the opening of said loop and diverging within the loop, said arms resiliently resisting their withdrawal through said opening by a pull on said member and automatically 55 returning to a position within said loop when the pull is discontinued.

3. The combination with a supporting strap embodying a loop, said loop having an opening formed therein, of an attaching 60 member embodying arcuately curved arms slidably extending through the opening of said loop, said arms resiliently resisting their withdrawal through said opening by a pull on said member and returning to 65 their normal position upon discontinuation of the pull.

4. The combination with a supporting strap embodying a loop, said loop having an opening formed therein, of an attaching 70 member embodying resilient arms extending through said opening and normally disposed within the loop and diverging from one another, whereby said arms resist a pull on said member tending to withdraw the arms 75 through the opening of the loop and automatically return to their normal position upon discontinuation of the pull, the ends of said arms embodying hook portions engaging the sides of said openings to limit 80 the movement of the arms therethrough.

In testimony whereof I hereunto affix my signature.

JESSE R. SMITH.
